UNITED STATES PATENT OFFICE.

JOSEPH H. STONE, OF ESCONDIDO, CALIFORNIA.

SPRING CONSTRUCTION.

1,277,663.

Specification of Letters Patent.

Patented Sept. 3, 1918.

Application filed December 5, 1916. Serial No. 135,232.

To all whom it may concern:

Be it known that I, JOSEPH H. STONE, a citizen of the United States, and a resident of Escondido, in the county of San Diego and State of California, have invented a certain new and useful Improvement in Spring Construction, of which the following is a specification.

My invention relates to improvements in springs, such as those which are used on vehicles of various kinds for taking up shocks and jars, and it consists in the combinations, constructions, and arrangements herein described and claimed.

15 An object of my invention is to provide a device which is so constructed as to be equally elastic under light or heavy loading.

A further object of my invention is to provide a spring having elastic qualities 20 against end shocks.

25 A further object of my invention is to provide a construction, in which one spring is initially brought into play with light loads, and both springs are brought into play under heavy loads.

Other objects and advantages will appear in the following specification, and the novel features of the invention will be particularly pointed out in the appended claims.

30 My invention is illustrated in the accompanying drawings forming part of this application, in which:

Figure 1 is a side view of a spring constructed according to my invention;

35 Fig. 2 is a detail view of a portion of the spring shown in Fig. 1, certain parts being shown in section;

Fig. 3 is an enlarged section on the line 3—3 of Fig. 2;

40 Fig. 4 is an enlarged section on the line 4—4 of Fig. 2, and

Figs. 5, 6, and 7 are modified forms of the spring.

45 The main feature of my improved spring is in providing a spring construction in which an upper spring is first brought into play under a light load, while a lower spring is brought into play when the upper spring has been moved to a given position, depending upon the size of the spring and its particular relation with respect to the lower spring.

In Fig. 1 I have shown upper springs 1 which are secured at 2 to the body portion 55 of the vehicle in any suitable manner. The ends of these springs 1 are made elastic and

bent downwardly as shown at 3. The spring is bent inwardly as shown at 4 and then upwardly, forming a loop. In the present instance, *i. e.*, in that form shown in Figs. 1 and 2, the end of the spring is passed around a pin 6 carried by a hanger 7.

Each of the springs 1 is bent at its ends and is secured in the manner described. In fact, the springs 1 in Fig. 1 might be a single 65 spring, for instance as shown in Figs. 5 and 6, without departing from the spirit of the invention.

A lower heavy spring 8 is secured to the axle 9 in any suitable manner. It will be observed that the ends of this spring 8 are bent upwardly, as shown at 8^x, and are made lighter and more elastic. These ends are brought around downwardly and inwardly substantially concentric with the loops of 75 the upper spring. The end of the lower spring is provided with a roller 10 and is loosely disposed between the hooked portion of the upper spring, so as to slide therebetween. At 11 I have shown a series of anti-friction rollers carried by the lower spring, and which are arranged to be engaged by the upper spring, as will be explained later.

From the foregoing description of the various parts of the device, the operation 85 thereof may be readily understood.

When initial pressure comes on the upper spring it will move from the full line position shown in Fig. 2 to the dotted line position, in which the upper spring will tend to leave the lower spring. If the weight is relatively light the upper spring alone will be brought into play, but if the weight is greater, then, on further pressure of the upper spring, it will come into contact with the upwardly turned end of the lower spring, substantially at the place where the roller bearings are situated. The lower spring is now brought into play, and the end will move with respect to the end of the upper spring.

In order to prevent noise I may insert an elastic cushion 12 between the curved portions of the upper and lower springs, as shown in Fig. 2. This may be made of any suitable material, such as rubber, leather, etc.

The ends of the lower spring being fitted to the ends of the upper spring, brace the upper spring against endwise motion of the vehicle. The extension of the upper spring ends around above the bottom portions of the inner spring, prevents excessive recoil.

In Figs. 5, 6 and 7 I have shown modified forms of the device which, however, depend upon the same principle, *i. e.*, that of an upper spring which acts with light loads and which subsequently brings into action a lower spring with heavier loads. In Fig. 5 the upper spring 13 is looped around the end 14^x of a lower spring 14. The two ends 14^x and 13^x are secured together, but the action is substantially the same, since the upper spring will tend to be bowed outwardly away from the inner spring when the light load is brought into play, and on further flexure of the upper spring it will come in contact with the lower spring, tending to force the upwardly bent ends downwardly.

In Fig. 6 the spring 15 is looped around and has its end 15^x secured to a bracket 17. The end 16^x of the lower spring is also secured to this bracket. It will be seen that the relations of the ends of the upper and lower springs are, however, substantially the same, so that the upper spring will take the initial load and subsequently bring into play the lower spring.

In Fig. 7 the upper spring 18 and the lower spring 19 have the same relation as the springs 15 and 16 in Fig. 6.

I am aware that other forms of springs might be made which are based on the same general principle without departing in the least from the spirit and scope of the invention.

I claim:

1. In a spring construction for vehicles, the combination with an upper spring member adapted to be secured to the body of the vehicle, and having a downwardly and inwardly curved portion, of a second spring member having a curved portion fitting within the curved portion of the first spring member, and having its weight receiving portion normally spaced from the first spring member, and said second spring member being movable independently of the first spring member.

2. In a spring construction, the combination with an upper spring member, adapted to be secured to the body of the vehicle, and provided with downwardly extending inwardly curved portions, of a second spring member adapted to be secured to the axle, and having similarly curved portions fitting within the curved portions of the first spring member, and connections between said curved portions for permitting independent movement of said curved portions relative to each other, and said second spring member having its weight receiving portion normally spaced from the weight receiving portion of the first spring member, whereby the first spring member is brought into play under light loads, and both springs brought into play under heavy loads.

JOSEPH H. STONE.
